UNITED STATES PATENT OFFICE

ARMIN H. WITTENBERG, OF LOS ANGELES, CALIFORNIA

STOCKING

Application filed June 30, 1930. Serial No. 464,764.

My invention relates to a reinforced stocking and has particular reference to a stocking of the full-fashioned type with a reinforcing member placed in the stocking at the upper part of the leg portion in the seam by means of which the stocking is held together, the reinforcing member forming a part of the seam and being placed in the seam at the juncture of the lower edge of the downwardly folded portion of the stocking where it is admitted into or joined to the body of the stocking.

Another and further object of my invention is the provision of a reinforcing member by means of which the seam at the upper portion of the stocking is reinforced and breaking out of the seam is prevented, thereby strengthening the stocking at this particular point.

Another and further object of my invention is the provision of a reinforced stocking having a woven member sewed into the seam only, whereby the seam is materially strengthened and the free edges of the reinforcing member are unattached from the stocking or attached only with a stitch or two so as to hold them flat, thereby preventing any drawing or breakage of the threads of the stocking, and allowing this portion of the stocking to remain smooth.

These and other objects of my invention will be more fully and better understood by reference to the accompanying sheet of drawings and in which—

Figure 1 is a rear elevational view of a stocking embodying my invention;

Figure 2 is an elevational view of the upper portion of the stocking with the front portion of the stocking broken away and showing the reinforcing member attached to the rear of the stocking; and

Figure 3 is a transverse sectional view on line 3—3 of Figure 2.

Referring now specifically to the drawings and in which like reference characters refer to like parts throughout, a stocking 10 is shown of the full-fashioned type having a longitudinally extending seam 11 at the rear thereof by means of which the sections of the leg portion of the stocking are secured

together. In forming the full-fashioned stocking it will be understood that the leg portions are knitted in flat form and with the edges of the sections free, the edges thereafter being stitched together to fashion the stocking into its tubular form as finally worn.

In the manufacture of stockings it has been the practice to form the top portion of the stocking of double layers of material by forming the sections of the stocking of additional length and folding the top portion of the stocking down a predetermined distance and knitting the free ends of the warp threads into the fabric body of the stocking along the line 12, as shown in Figures 1 and 2, thereby providing a cuff or reinforced stocking top of two layers of material to which the hose supporters or other fastening means are attached, this double thickness affording greater wear-resisting qualities than would be the case if a single thickness of material were used. When the stocking is seamed up the free edges of the portions are sewed together by the continuous seam 11.

In stockings as ordinarily manufactured, due to the stresses placed upon the stocking by the supporters and the bending stresses upon the threads of the stocking when the leg of the wearer is flexed, an unusual amount of stress is placed upon the stocking where the stitching 11 crosses the line 12 where the cuff portion is joined to the single layer of the stocking, so that the seams tear, causing the stocking to break and run at this point, particularly in the finer grades of hosiery made up of extremely fine silk threads. In my improved stocking I place a reinforcing member 13 on the inside of the stocking at the rear portion thereof, this member being made of linen cloth, or other suitable finely woven material having a maximum amount of strength, and is seamed into the stocking by the line of stitching 11 so that the member 13 forms an integral part of the row of stitching 11 by means of which the sections of stocking are secured together. This member 13 can be slightly oval in shape or circular, as the case may be, or may be a narrow tape

of sufficient width so that it is caught by the threads which make up the line of stitching 11.

The proper form is shown in Figures 1 and 5 2 with stitches 14 and 15 at the sides thereof to hold the member 13 down against the body of the stocking. The stitching is very light and will not cause the threads to pull or break but is merely intended to hold the member 13 10 in flat condition and prevent its rolling. This member being much stronger than the threads making up the stocking, forms a reinforcing member which supports the stitches at this point and also reinforces the 15 seam preventing the tearing out of the stitches or the breaking of the threads in the stocking on each side thereof, thus materially adding to the life of the stocking.

In inserting the reinforcing member in the 20 stocking it is only necessary to place it in position during the sewing operation and it is sewed into the stocking at the same operation by means of which the sections of the stocking are secured together.

25 While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

30 1. A full-fashioned stocking having a double knit top portion and a reinforcing member sewed into the longitudinally extending seam of the stocking and extending to a point below where the double knit top portion of the stocking is joined to the body 40 of the stocking.

35 2. A full-fashioned stocking having a double knit top portion and a reinforcing member of strong woven material sewed into the longitudinally extending seam of the stocking forming the junction of the sections thereof and extending below the lower edge of the double knit portion or top portion of the stocking.

45 3. A full-fashioned stocking having a double knit top portion and a reinforcing member of strong woven material sewed into the longitudinally extending seam of the stocking where the double knit portion or top portion of the stocking is joined with the body 55 portion thereof the reinforcing member being stitched to the stocking at the sides thereof at the line of juncture of the double knit portion of the stocking and free at its other marginal edges.

60 4. A full-fashioned stocking having a double knit top portion and a reinforcing member sewed into the longitudinally extending seam of the stocking at the rear of the upper leg portion of the stocking.

65 5. A full fashioned stocking having a dou-

ble knit top portion, a line of stitching forming a seam at the rear of said stocking and extending longitudinally thereof throughout its entire length whereby the said stocking is held in tubular form, and a reinforcing member secured to and forming a part of the said seam at the point of juncture of the double knit portion with the body of the stocking at the top thereof and extending a short distance above and below the point of juncture.

Signed at Chicago, Illinois, this 24th day of June, 1930.

ARMIN H. WITTENBERG.
